L. E. EARLE

BEATER

Filed May 20, 1925

UNITED STATES PATENT OFFICE.

LEE EDGAR EARLE, OF ALBANY, NEW YORK, ASSIGNOR TO UNITED ROYALTIES CORPORATION, OF NEW YORK, N. Y.

BEATER.

Application filed May 20, 1925. Serial No. 31,651.

This invention relates to improvements in beaters which are particularly intended for culinary use.

The primary object of the present invention is to provide means for preventing the beater pinions from becoming disengaged from the driving gear, thereby causing the pinions to become either locked or thrown out of operation with the driving wheel or gear.

A further object of the present invention is to provide means located under the pinions to prevent them from becoming disengaged from the driving gear, or prevent them from being disengaged and then locked with the driving gear.

A further object of the present invention is to provide the supporting frame for the gears of the beater with a bridge that extends under the pinions of the beaters thereby preventing them from becoming disengaged with the driving gear, and again engaged in locked relation to the driving gear.

Another object of the present invention is to provide a supporting frame for the driving gear and beater pinions with an attachable bridge that extends beneath the pinions thus preventing them from being disengaged from the driving gear, thereby being either inoperative or caused to again engage the driving gear in locked relation therewith.

Further objects of the present invention will appear from the following description:

In the accompanying drawings:

Figure 1 is a side elevation of a beater that involves the present improvement.

Figure 2 is a transverse sectional view on line 2—2 of Figure 1 looking in the direction indicated by arrow.

Figure 3 is an enlarged vertical sectional view taken through the center of the bridge which involves the improvement herewith disclosed.

Figure 4 is a detached plan view of the blank which forms the bridge.

Figure 5 is a vertical sectional view taken through the lower portion of the driving wheel, the pinions, the bridge and the upper ends of the beater blades.

The present invention involves the type of beater which is disclosed in the patent

granted to Ladd July 7, 1908, No. 892,856.

Referring now to the drawings, it will be observed that the present improvement involves a supporting frame 1 having attached to its upper end a suitable handle 2. This frame extends downward as shown and has its lower end provided with a U-shaped lateral extension 3 which has a transverse opening 4, in which opening the pinions 5 are located. A driving wheel 6 is centrally journaled at 7 on the supporting frame 1 and carries a suitable handle 8 by means of which it is rotated. It will be observed that in this type of beater the teeth 9 of the driving wheel 6 pass between the pinions 5 which pinions engage the teeth as shown. These teeth preferably are turned laterally for the purpose of engagement with the pinions so that they may engage opposite sides of the teeth 9 without interference.

A suitable rod has its ends 10 attached to opposite sides of the lateral extension 3 of the supporting frame 1.

The beater blades 11 are journaled on the upwardly extended portions of the rod 10, and attached to the upper ends of these beater blades are the pinions 5. It will be observed that in this construction the pinions are loose, and must be loose on the vertical extensions of the rod 10. Therefore the beater blades may be referred to as floating on the vertical portions of the rods, and consequently the pinions 5 attached to the upper ends of the beater blades are likewise floating on the said rod.

Therefore heretofore in this type of beater these pinions are maintained in engagement with the driving wheel 6 by reason of the beater blades 11.

By reason of this construction of beater difficulty has arisen by reason of the pinions becoming disengaged from the driving wheel. For years it has been found that one or more of these pinions may be disengaged from the driving wheel 6 by a lateral expansion of the beater blade that carries it, and that when engaged again with the driving wheel, it happens not to be in its proper position, then the driving gear and the beater blades become locked so that the device is inoperative.

This has been found to occur under sev-

eral conditions. One condition being that when the merchant removes the wrapping from a dozen or more of these beaters and they are laid in the box on his counter, and 5 a woman or other person in a hurry takes up one of these beaters and pulls it free from the remaining beaters, causes the lateral expansion of the beater blades and thereby causes the floating pinion 5 to be disengaged 10 from the driving wheel, and when again free engages the driving wheel in a different position, in which it is locked, making the device inoperative. Such a condition naturally leads the person to believe the device is readily distorted to make it inoperative, and destroys the sale of it.

Second, it has been found that in handling beaters in the kitchen the blades have been struck against the table in such a manner 20 as to cause the disengagement of the floating pinion with the operating wheel, causing the same result.

Third, some people use the beaters in a very heavy sticky material thereby over- 25 working them which causes the lateral expansion of the blades in withdrawing the beater from the mixture, thereby causing the floating pinion to disengage the driving gear, and possibly when engaging it again 30 causes the locking of the parts above referred to.

The foregoing defects are not due to any bad material or workmanship but is due to the inherent construction of the device. 35 While the above result has been known for a good many years no manner has been suggested of curing the result. Finally the applicant has devised the method which will now be described of preventing the disengagement of these floating gears with the operating wheel thereby overcoming absolutely the conditions above recited.

This improvement consists of a bridge 11 that extends across the opening 3 beneath 45 the pinions 5 and between them so that if the beater blades 11 are laterally expanded for the above reasons, or in any manner are drawn down they then engage the transverse bridge 12 thus preventing them from 50 being pulled out of engagement with the driving wheel.

This improvement as here shown is of such a form that it is attachable to the construction as it is being made.

55 This device is attachable by having its ends somewhat elongated and doubled backward as shown at 13 around the part 14 of the laterally bent portion of the supporting frame. For the purpose of making the attachment more permanent than would otherwise be the case the part 14 is bent downward as at 15 into a downwardly bent portion 16 of the clip 12 thus uniting them and holding the clip from lateral movement on 60 the supporting frame. Attention is direct-

ed to the fact that the center portion 17 of the bridge 12 is bent upward and lies substantially close to the floating pinions thus preventing them from being depressed out of engagement with the driving wheel 6. 70 By reference to Figure 4 it will be seen that this clip 12 has its ends somewhat enlarged while its central portion 17 is made narrow to pass between the said pinions without engaging the beater blades 11, and the enlarged heads provided with the ends 13 which are doubled around the part 14.

75 While the construction has been described in detail, yet I do not limit my invention to the details of construction shown, but any 80 construction within the scope of the appended claims would involve my present improvement.

Having thus described my invention what I claim is:

85 1. A beater comprising a vertical frame having at its lower end a laterally extending portion formed with a pinion opening, a pinion located in the said opening and carrying beater blades, and a bridge extending across the said opening connected to opposite portions of the supporting frame by being bent around the latter for preventing the disengagement of the pinion from the driving gear.

90 2. A beater comprising a vertical frame having a vertical driving gear the lower end of the frame having lateral extensions having a pinion opening, a pinion located in the said opening, a bridge connected to the laterally bent lower end of the frame by having its ends bent therearound, the bridge having a reduced central portion whereby it may be extended below the teeth in the pinion for preventing it becoming disengaged from the driving wheel.

95 3. A beater comprising a vertical frame, a vertical driving gear carried by the said frame, the lower end of the frame turned laterally and having pinion openings, a rod 100 upon which the pinions are journaled, a bridge having a reduced central portion passing below the said pinions for the purpose described, and the ends of the bridge having ears which are doubled around the 105 laterally bent portion of the frame.

110 4. A beater comprising a vertical frame carrying a vertical driving wheel, said frame having a laterally bent lower end provided with pinion openings, pinions located in the said openings carrying beater blades, a bridge extending between and below the said pinions, for the purpose described, the ends of the bridge bent around the said frame and the laterally bent portions of the frame 115 and the said bridge being bent together whereby it is locked in position.

120 5. A beater comprising a vertically U shaped frame having a transverse opening which forms parallel portions at each side 125 130

of the opening, a pinion located in the opening, an operating wheel carried by the frame and engaging the said pinion, the frame having a horizontal bridge in substantially the same horizontal plane as the lower portion of the U-shaped frame, the bridge extending below the said pinion and spanning the

said opening, said bridge having the edge of its horizontal portion cut away to form a vertical opening for said pinion, the parts ¹⁰ operating as described.

In testimony whereof I hereunto affix my signature.

LEE EDGAR EARLE.
